E. F. KELLIE

FLOOR CONSTRUCTION

Filed Oct. 27, 1920

INVENTOR.

Edward F. Kellie

BY

W. Bradford

ATTORNEY.

UNITED STATES PATENT OFFICE.

EDWARD F. KELLIE, OF INDIANAPOLIS, INDIANA.

FLOOR CONSTRUCTION.

Application filed October 27, 1920. Serial No. 419,887.

To all whom it may concern:

Be it known that I, EDWARD F. KELLIE, a citizen of the United States, residing at Indianapolis, in the county of Marion and 5 State of Indiana, have invented certain new and useful Improvements in Floor Construction, of which the following is a specification.

My said invention consists in the construction and composition of a fire proof floor, or 10 similar structure, combining great wear resisting qualities with unusual hardness and strength, and one that will not crack under ordinary strain, all as will be hereinafter 15 more fully described and claimed.

Referring to the accompanying drawings, which are made a part hereof and on which similar reference characters indicate similar parts,

20 Figure 1 shows a section through a floor constructed in accordance with my said invention, and

Figure 2 is a plan view showing the various layers at different points in the floor.

25 The I-beams A and base structure B are or may be of any reinforced concrete construction and require no special description. On the top of base B, a layer 10 is placed consisting of a mixture of one part of Cemite 30 cement and three parts of "Joplin chat" or zinc refuse, or crushed flint rock of a size that will pass through a $\frac{1}{4}$ or $\frac{1}{2}$ inch mesh screen. To this I add 2 lbs. of satinette asbestos (short fiber) to each sack of Cemite

35 cement used with the mixture. This is spread over the concrete base in a layer $2\frac{1}{2}$ to 3 inches thick. On top of this I apply a web 11 of flexible veneer strips approximately one inch wide and $\frac{1}{8}$ of an inch thick

40 woven into an open basket weave and applied on the base while wet, and substantially imbedded therein. On top of this I spread a layer 12 comprising an aggregate of marble, granite or flint rock chips reduced

45 to $\frac{1}{2}$ inch mesh of a variety of colors and evenly distributed over the Cemite cement and imbedded therein. I then spread a surface layer 13 formed of a mixture of Cemite cement and asbestos (short fiber) in the pro-

50 portion of 3 lbs. of asbestos to each bag of cement which is poured over the marble or stone chips to entirely cover them. The mass is then allowed to cure for approximately three days when a rotary smoothing 55 machine equipped with carborundum blocks

is pushed over the entire surface until the surfaces of the aggregates are exposed and the surface is perfectly smooth. By this means a floor is provided of a "mottled" appearance, quite attractive in character, and 60 one that is tough and capable of resisting unusual wear and strain.

At points above the posts or supporting columns a section 14 of wire mesh or similar reticulated material is placed to reinforce the floor at such points.

Having thus fully described my said invention, what I claim as new and desire to secure by Letters Patent, is:

1. A floor, etc., for fire proof buildings, 70 comprising a reinforced fire proof base, a layer of a mixture composed of cement and crushed rock on said base, a web formed of strips of veneering on top of said mixture and another layer of crushed stone on top of 75 said web, and then a layer of cement mixed with fiber covering said last material, substantially as set forth.

2. A fire proof floor construction comprising a supporting base, a floor base over 80 said supporting base composed of a mixture of cement, crushed rock and fiber, a flexible binder imbedded in the upper surface of said floor base composed of flexible strips, a layer composed of a mixture of crushed mineral substance over said flexible strips, and a top layer composed of a mixture of cement and fiber, substantially as set forth.

3. A floor, etc. for fire proof buildings 90 comprising a base consisting of a mixture of cement and crushed mineral, a flexible web on top of said base, a layer of crushed mineral on top of said web, and a surface layer consisting of cement mixed with fiber with 95 portions of the crushed mineral exposed, substantially as set forth.

4. A floor etc., for fireproof buildings comprising a base mounted on supporting columns, a layer of Cemite cement and 100 crushed mineral on said base, a flexible web on said layer, a section of re-enforcing material embodied in the base above the supporting columns, a layer of crushed mineral on said web, and a surface layer composed 105 of Cemite cement and fibre, substantially as set forth.

5. A floor, etc., for fire proof buildings, comprising a reinforced fire proof base, a layer of a mixture composed of cement and 110

zinc refuse on said base, a web formed of strips of veneering on top of said mixture and another layer of crushed stone on top of said web, and then a layer of cement mixed with fiber covering said last material, substantially as set forth.

In witness whereof, I have hereunto set

my hand and seal at Indianapolis, Indiana, this 12th day of October, A. D. nineteen hundred and twenty.

EDWARD F. KELLIE. [L.S.]

Witnesses:

E. W. BRADFORD,
M. L. SHULER.
